UNITED STATES PATENT OFFICE

121,157

DESIGN FOR A SLIPPER OR SIMILAR ARTICLE

Paul D. Earl, New York, N. Y.

Application May 4, 1940, Serial No. 92,165

Term of patent 3½ years

To all whom it may concern:

Be it known that I, Paul D. Earl, a citizen of the United States of America, residing in the city of New York, county of New York, and State of New York, have invented a new, original, and ornamental Design for a Slipper or Similar Article, of which the following is a specification, reference being had to the accompanying drawing, forming part thereof.

Fig. 1 is a plan view of a slipper or similar article showing my new design.

Fig. 2 is a side elevational view thereof.

I claim:

The ornamental design for a slipper or similar article, substantially as shown.

PAUL D. EARL,
